BONE DUST SCRAPER

Joachim R. Beltram, Livingston, N.J., assignor to International Edge Tool Co., Newark, N.J., a corporation of New Jersey

Filed May 1, 1961, Ser. No. 64,995

Term of patent 14 years

(Cl. D11—1)

Fig. 1

Fig. 2

Fig. 3

FIG. 4

FIG. 5

FIGURE 1 is a top plan view of a bone dust scraper embodying my new design.

FIGURE 2 is a side elevational view thereof.

FIGURE 3 is a bottom view thereof.

FIGURE 4 is an end view of the bone scraper as viewed from the handle portion thereof.

FIGURE 5 is an end view of the scraper as viewed from the band portion thereof.

The bone dust scraper disclosed is characterized by the particular shaped handle.

I claim:

The ornamental design for a bone dust scraper, substantially as shown and described.
